UNITED STATES PATENT OFFICE.

REUBEN B. BENJAMIN, OF CHICAGO, ILLINOIS, ASSIGNEE TO BENJAMIN ELECTRIC MANUFACTURING COMPANY, OF CHICAGO, ILLINOIS, A CORPORATION OF ILLINOIS.

ELECTRICAL-FIXTURE-SUPPORTING DEVICE.

Application filed May 20, 1921. Serial No. 471,075.

To all whom it may concern:

Be it known that I, REUBEN B. BENJAMIN, a citizen of the United States, residing at Chicago, in the county of Cook and State 5 of Illinois, have invented new and useful Improvements in Electrical-Fixture-Supporting Devices, of which the following is a full, clear, concise, and exact description, reference being had to the accompanying 10 drawing, forming a part of this specification.

My invention relates to electrical fixture supporting devices and connections therefor.

One of the objects of my invention is to 15 provide an improved fixture supporting device in which the fixture can be readily connected and disconnected with respect to the receptacle, both electrically and mechanically.

20 A further object of my invention is to provide such a device which will be simple in construction, cheap to manufacture and durable and efficient in use.

Further objects will appear from the 25 detailed description to follow and from the appended claim.

In the drawings in which an embodiment of my invention is shown—

Fig. 1 is a vertical axial section showing 30 the fixture, receptacle and connector device;

Fig. 2 is a vertical sectional view showing the supporting plate and connecting device;

Fig. 3 is an inner face view showing the 35 plug and connecting bracket; and

Fig. 4 is a face view of the receptacle.

The construction shown in the drawing comprises a fixture 10 (the stem 11, and canopy 12 alone being shown) an electrical receptacle 13, a plug-in device 14 for electrically connecting the fixture 10 with the receptacle 13, and a mechanical connecting member or bracket 15 for mechanically connecting the fixture with respect to the receptacle.

45 The plug-in device 14 is carried by the connecting bracket 15, being bodily slidably mounted thereon, to permit the necessary movement of the connecting bracket 15 for making the mechanical connection without interfering with the insertion of the contact blades 16 into the openings 17 provided in the receptacle.

The mechanical connector member 15 is 50 secured to the supporting plate 18 (which may be a sort of cover for the outlet box)

by means of two hook members 19, which hook over the edges of the notches 20 in the supporting plate 18 (Figs. 2 and 4). The connection between the connecting bracket 15 and the supporting plate 18 is effected by movement of the bracket inwardly and downwardly with respect to the receptacle 13 and supporting plate 18, to bring the hook members 19 in back of the supporting plate 18, and down back of the edges of the notches 20.

The sliding connection between the plug-in device 14 and the connecting bracket 15 hereinbefore referred to permits the downward movement of the connecting bracket 15 without interference from the engagement of the blades 16 in the opening 17, that is to say, it permits the blades 16 to be pushed straight in at the same time permitting the connecting bracket 15 to be pushed in and also to be moved downwardly to effect the engagement of the hooks 19 with the supporting plate 18. This sliding connection of the plug-in device with the connecting bracket 15 is effected by a pair of lugs 21 and 22, struck up from and formed integral with the bracket 15, these lugs engaging corresponding notches 23 and 24 in the insulating base 25 on which the contact blades 16 are mounted. The insulating base 25 is thus slidably mounted between the strap members 26 of the bracket 15, and the lugs 21 and 22. The lugs 21 and 22 by their engagement in the notches 23 and 24 prevent the insulating base 25 from slipping sideways. It will be noted that the lugs 21 and 22 are of different widths, as are also the notches or recesses 23 and 24, thus assuring the proper assembly of the plug-in device 14 with respect to the bracket 15.

The connecting bracket 15 may be an integral sheet metal stamping, having the hook members 19 and the lugs 21 and 22 formed integral therewith and struck up therefrom.

For connecting the fixture 10 to the bracket 15, the canopy 12 may have secured to it a pair of transversely extending metal straps 27, which may be secured to the ends of the bracket 15 by means of screws 28.

A suitable ornamental finishing plate or escutcheon 29 may be secured to the supporting plate or cover 18 by means of screws 30.

The wires for the fixture 10 lead from the fixture stem 11 through the central opening 31 in the insulating base 25 to the binding 110

screws 32, which are threaded into the contact blades 16 of the plug-in device 14.

For electrically and mechanically connecting the fixture with respect to the receptacle 13, the entire device comprising the fixture 10, bracket 15 and plug-in device 14 is presented to the receptacle in such position that the contact blades 16 are in position to enter the openings 17 in the receptacle, and in such position that the hook members 19 on the bracket can be inserted into the notches 20 in the supporting plate 18.

The entire device, including the fixture 10, the bracket 15, and the plug-in device 14 is then pushed inwardly to cause the contact blades 16 to enter the openings 17 in the receptacle, and to cause the hook members 19 to enter in back of the supporting plate 18. The fixture 10 and supporting bracket 15 are then shifted downwardly to cause the ends of the hook members 19 to engage in behind

the edges of the notches 20 to hold the bracket 15 securely in position on the supporting plate 18.

Having thus described my invention, what I claim as new and desire to secure by Letters Patent of the United States is:

A mechanical and electrical connector device comprising a fixture supporting bracket and a plug slidably mounted on said bracket, said bracket being formed of sheet material and having two flat vertical bars lying in a common plane in front of the plug and having cross bars at the top and bottom connecting the vertical bars and lugs extending toward each other from said cross bars, said plug being slidably mounted between the two vertical bars and the lugs. 35

In witness whereof, I have hereunto subscribed my name.

REUBEN B. BENJAMIN.
